UNITED STATES PATENT OFFICE

100,031

DESIGN FOR A LAMP BASE OR SIMILAR ARTICLE

Harry M. Laxer, New York, N. Y., assignor to
Idealite, Inc., New York, N. Y., a corporation
of New Jersey

Application March 19, 1936, Serial No. 61,694

Term of patent 3½ years

To all whom it may concern:

Be it known that I, Harry M. Laxer, a citizen of the United States and a resident of the city, county, and State of New York, have invented a new, original, and ornamental Design for a Lamp Base or Similar Article, of which the following is a specification, reference being had to the accompanying drawing, forming part thereof:

In the drawing, the figure is a perspective view of a lamp base or similar article showing my new design.

The appearance of both sides of the lamp base or similar article is identical, except that the

outlines on the globe are in accordance with the geographic fact.

The particular feature of the present invention resides in the circular base supporting member having the enlarged pair of balls arranged at diametrically opposite points and on opposite sides of the central raised portion, with the ring-like frame intersecting these balls and the upper portion of the base supporting member.

I claim:

The ornamental design for a lamp base or similar article, as shown and described.

HARRY M. LAXER.
